UNITED STATES PATENT OFFICE.

HARRY P. HUNTER, OF MOUNT VERNON, OHIO, ASSIGNEE TO THE PITTSBURG PLATE GLASS COMPANY, OF PITTSBURGH, PENNSYLVANIA, A CORPORATION OF PENNSYLVANIA,
Air-Supply Regulating Means.

4,181,853.

Specification of Letters Patent.

Patented May 30, 1916.

Application filed July 6, 1911. Serial No. 627,199.

To all whom it may concern:

Be it known that L. HARRY P. HUNTER, a citizen of the United States, residing at Mount Vernon, in the county of Knox and 5 State of Ohio, has invented certain new and useful Improvements in Air-Supply-Regulating Means, of which the following is a specification.

The invention relates to regulating means 10 for controlling the pressure in an air supply system. The apparatus is designed particularly for use with window glass forming mechanism, wherein large glass cylinders are drawn, and to the interior of which a 15 considerable volume of air under relatively low pressure must be supplied at a uniform pressure. The invention has for its objects; the provision of an air supplying apparatus adapted to supply a quantity of air at relatively low pressure with a close regulation of such pressure; and the provision of an apparatus in which the pressure is controlled directly and positively from the portion of the system from which the distribution of the air occurs. The invention is 20 illustrated in the accompanying drawing, wherein:—

The figure is a view, partially in section, showing the preferred arrangement of the 25 apparatus.

Referring to the drawing; 1 is a fan for supplying air pressure to the system; 2 is the supply pipe, preferably of large diameter in order that the supply of air may be 30 uniform in pressure; 3, 4, 5, 6, 7, 8, 9, and 10 are a series of what may be termed distributing pipes leading from the supply pipe 2 to the blow pipes of the glass drawing machines; 11 is a valve preferably of the 35 butterfly type for controlling the supply of air to the outlet side of the pipe 2; 12 is the pressure regulating tank provided with the usual annular compartment 13 for carrying the liquid seal; 14 is the cap or cover of the 40 tank having its edge in the liquid in the compartment 13 and carrying the post 15 having connection with the crank arm of the butterfly valve by means of the connecting rod 16; and 17 is a controlling pipe connected 45 at one end to the regulating tank 12,

and at the other end connected to the distributing portion of the pipe 2 by means of the plurality of branches 18 and 19.

In order to provide a guide for the post 15, the cylinder 20 is mounted in the tank 55 12, and braced against lateral movement by means of the rods 21. The post 15 is also similarly braced from the upper portion of the cap by means of the rods 22. As shown, the post is guided at the top and bottom of 60 the cylinder 20, but other guiding arrangements for the post might obviously be substituted. The provision of the guides insures the sensitive operation of the apparatus, as by this means, the cap and tank are 65 held in concentric relation, and the friction incident to the relative movement of the cap and tank reduced to a minimum. The sides of the tank and cap are also maintained in parallelism, and a direct and positive connection between the cap and the valve 11 is secured.

The connection of the controlling pipe 17 to the supply pipe 2 at a point adjacent the point of the distribution is advantageous, 75 inasmuch as the point of distribution is the point in the system at which a uniform pressure is desired, and the arrangement provides a direct and immediate control of the regulating mechanism from this point. The 80 provision of the plurality of branches 18 and 19 secures a control depending upon the mean pressure in the distributing portion of the pipe 2, so that a substantially uniform pressure is secured in the various distributing pipes.

Having thus described my invention and illustrated its use, what I claim as new and desire to secure by Letters Patent is the following:—

In combination in an air supply system; a means for supplying air under pressure; a supply pipe leading therefrom; a plurality of distributing pipes connected to the said supply pipe; a throttling valve in the supply pipe; a regulating tank; a regulating cap mounted for vertical movement in the tank; a liquid seal between the tank and cap; a connection from the cap to the valve for securing a closing movement of the 100

valve as the cap rises; and a controlling means connected at one end to the tank and including a plurality of branches connected at different points along the portion of the supply pipe carrying the distributing pipes whereby the cap is governed by the mean pressure at this part of the supply pipe.

In testimony whereof I have hereunto signed my name in the presence of the two subscribed witnesses.

HARRY F. HITNER.
